DECORATIVE HANGING ELEMENT

William W. Williams, West Hollywood, Calif.
(954 19th St. W., Costa Mesa, Calif.)

Filed June 17, 1965, Ser. No. 85,779

Term of patent 14 years

(Cl. D29—1)

I claim:

The ornamental design for a decorative hanging element, as shown and described.
